PORTABLE ELECTRIC FLASHLIGHT

Bernard Francis Muldoon, Caldwell, N. J., assignor to Henry Hyman, New York, N. Y.

Application September 21, 1943, Serial No. 503,182

19 Claims. (Cl. 240—10.67)

1.

This invention relates to portable electric flashlights, and particularly those of the angle head type.

One of the objects of the invention is to provide a flashlight of the character described having a casing made of plastic material which is so constructed that it will not deform or break under severe service conditions such as extreme cold or extreme dry or moist heat.

Another object of the invention is to provide a flashlight of the character described which shall comprise relatively few and simple parts and be highly efficient in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claims.

Certain features shown and/or described and not claimed herein are shown, described and claimed in my copending applications Serial No. 377,983, filed February 8, 1941, and Serial No. 503,183, filed September 21, 1943, now respectively Patent No. 2,401,366 dated June 4, 1946, and Patent No. 2,358,820 dated September 26, 1944.

In the accompanying drawings, in which is shown one of the various possible embodiments of this invention;

Fig. 1 is a side elevational view of a flashlight embodying my invention;

Fig. 2 is a longitudinal sectional view therethrough taken substantially along the line 2—2 of Fig. 1;

Fig. 3 is a longitudinal sectional view therethrough taken substantially along the line 3—3 of Fig. 2;

Figs. 4 and 5 are sectional views taken, respectively, substantially along the lines 4—4 and 5—5 of Fig. 3 being detail views of the head and rear assembly respectively;

Fig. 6 is a front to back sectional exploded view of the flashlight; and

Figs. 7 and 8 are sectional views taken, respectively, substantially along the lines 7—7 and 8—8 of Fig. 6.

Referring now in detail to the drawings, the angle head flashlight 10 embodying my invention there shown, comprises in general a battery casing 12, a head assembly 14, a base assembly 16 and an electrical system which includes a switch 18 and various parts of the head and base assembly.

The battery casing

The battery casing 12, which is fabricated from a moldable insulating material such, for

2.

example, as phenol condensate or cellulose acetate butyrate, comprises a body portion 20 which is integrally connected to a head portion 22. The body portion consists of a hollow cylindrical tube having an open bottom end which is provided with male threads 23 to receive the base portion. Immediately above the threads the body portion is provided with a circumferential reinforcing bead 24. Near the top end of the casing a similar bead 26 is provided to impart a balanced appearance to the casing. Intermediate these two beads, the exterior surface of the casing has a plurality of longitudinally extending ridges 28 molded therein to rigidify the casing thus imparting a high degree of strength thereto while still keeping the casing walls as thin as possible in order to minimize the weight of the flashlight and make for economy in manufacture.

The head 22 of the casing comprises a cylindrical tube of the same diameter as the body portion 20 and integrally molded therewith, the line of juncture between the head and body portions being rounded off at the back 30 of the head.

The front end of the cylindrical tube comprising the head portion has a set of male threads 32 formed therein for the head assembly 14.

Although disposed inside of the flashlight casing 12, the lower wall 34 of the tube forming the head 22 is left substantially intact (Fig. 2), integrally connecting one side of the body casing portion 20 with the diametrically opposed side thereof. This lower wall 34 forms a substantially arcuate, upwardly concave integral partition between the head and body portions of the casing and affords substantial reinforcement to these parts thereof, thus increasing the resistance of the casing to impact and rendering same less liable to deformation at high temperatures and under moist or dry atmospheric conditions.

The interior of the casing 12 is of special configuration to accommodate the parts of the electrical system without materially affecting the strength or ruggedness of the casing.

In the body portion a pair of longitudinal parallel spaced ribs 36 is provided which between them define a channel 38 narrowing slightly near the upper end of the body portion 20. It will be noted that the ribs 36 run beneath and alongside of the switch 18 thus reinforcing the casing where it is apertured and countersunk to accommodate the switch.

The upper end of the channel 38 extends through an opening 40 provided in the semi-cylindrical inner wall 34 of the head. Directly above this opening and above the end of the channel 38 a small tapered pin 42 extends integrally from the casing. Said pin runs parallel to the longitudinal axis of the head portion 22 and is secured thereto by an integral wall 44 which

stops short of the tip of the pin so as to provide a slot 46 whose walls are spaced radially of the longitudinal axis of the head portion and which faces toward the front of said portion. The front end of the head portion on which the male threads 32 are molded is of greater internal diameter than the back portion thereof which is integrally formed with the body 20.

The front and back portions of the head are joined by a flaring fillet 48. The high point of this fillet is so situated as to interpose a fixed obstacle between the inner wall 46a of the slot 46 and the forward inner edge 47 of the head portion 22. The purpose of this construction will be later explained in connection with the electrical system.

To facilitate molding of the casing in one piece, the semi-cylindrical reinforcing wall 34 may be cut out to provide another opening 50 to receive an abutting portion of the molding cores for the head and body. This opening 50 may, as indicated, be located at the back of the head portion. It is reinforced by a raised wall 52 which extends from side to side of the semi-cylindrical wall 34. In addition to reinforcing the semi-cylindrical wall and the casing in general, said wall coats in a manner later described with an element of the electrical system.

It is preferable to also reinforce the ends of the wall and this is accomplished by molding a pair of wings 54 between said walls and the adjacent parts of the head and body portions. Said wings are adapted to prevent rearward or forward deflection or deformation of the wall 52.

To expedite support of the flashlight casing, a conventional metallic spring hanger 56 is provided, the same being secured to the flashlight casing by a pair of rivets 58 whose shanks pass through apertures in the belt hanger and in the back wall of the body portion where the inner ends are spun over against a steel strip 60 inside of the casing. It will be noticed that in this region of the casing the same is provided on the exterior and interior with a wide ridge 28 and a flat 62, respectively, so that the casing is appreciably locally thickened to better resist de-forming stresses.

Finally the casing also has a plurality of apertures and depressions formed therein, which will hereinafter be described in detail, to position and hold various elements of the electrical system.

Disposed within the casing is the usual set of batteries B, snugly encased in an open ended fibrous sleeve 64 in such manner that the batteries are connected in series and the zinc cup 66 of the lower battery is accessible at the bottom end of the sleeve, while the metal tipped carbon pole 68 of the upper battery is accessible from the top end of the sleeve.

The head assembly

This assembly comprises a lens ring 70 of plastic material having a female thread 72 adapted to mesh with the male threads 32 at the front end of the head casing portion 22. The forward edge of said lens ring has an inwardly extending flange 74 which provides a seat 76 against which the lens 78 is adapted to abut. Said lens may be formed from any suitable transparent material such as glass or transparent plastic like methyl methacrylate, vinyl ester resin, vinyl acetal resin or cellulose acetate butyrate. The lens may be in the form of a flat circular disk as illustrated, since it is employed in conjunction with a parabolic reflector, the term

"lens" having been retained by the art although neither surface thereof is curved.

In back of the lens and clamped between the same and the front edge of the head portion 22 is the out-turned angular flange 80 of an electrical conductive parabolic reflector 82. Said reflector is assembled to form with an electric light bulb 84 a prefocused unit in which the reflector serves to conduct the current from one side of the battery B to the lamp. To this end the reflector may have clinched to the rear thereof a threaded ferrule 86 of electrically conductive material, the front end of the ferrule being inturned where it is clinched to the reflector to provide a seat 88 against which the flange 80 of the electric light bulb 84 is adapted to rest. The flange is pressed against its seat by a plug 92 of insulating material such as that from which the casing 12 is fabricated. Said plug is threaded into the ferrule 86, and to facilitate rotation thereof is provided with a plurality of ridges 94 formed around the rear flange 95. The center of the plug has a large bore 96 running therethrough in which there is freely received the base of the electric light bulb, while a central contact 98 projects beyond the flange 95 so that it may be easily contacted by an element of the electrical system.

The base assembly

The base assembly comprises a bottom closure cap 100 of plastic material similar to that from which the casing 12 is molded. The lower end of the cap is closed off by a bottom wall 102, the top end being open and provided with a female thread 104 which is adapted to mesh with the male threads 23 at the lower end of the body casing portion 20. Between the lower ends of the threads 104 and the bottom wall 102 a substantial space is provided, large enough to receive a goodly portion of a spare bulb 106 lying athwart the closure cap, the walls of said cap surrounding said space being thickened to form a ledge 108 against which the fitting 110 for carrying the spare bulb can be seated. Said fitting, which is made from a single piece of sheet metal, comprises a strap 112 whose two ends 114 are arcuately shaped so as to fit within the closure cap at the ledge 108. The center span 116 of the strap is raised and diametrically slotted as at 118 to accommodate a portion of the flange 120 of the spare bulb 106. The latter is retained by a pair of resilient fingers 122 struck out from the material of the strap and shaped in such fashion as to frictionally hold the base 124 of the spare lamp. The spare lamp fitting is pressed against its seat 108 by a tapering helical battery compression spring 126 of electrically conductive material, the small end of which is adapted to strongly press against the zinc cup 66 of the lowermost cell B, and the large end of which is adapted to rest upon the seat 108. The tip of the spring has an inturned finger 128 which is adapted, when the closure cap is screwed on the base of the flashlight casing, to press against the inner bottom edge thereof to effect a good electric contact with an element of the electrical system now to be described and which is positioned at this point.

The electrical system

The electric system comprises a ferrule 130 of electrically conductive material which is nested within the lower end of the casing portion 20 and is there held by an eyelet 132. The lower edge

of the ferrule is spun out over the bottom edge of the casing so as to insure contact with the spring finger 128. The ferrule 130 is connected to the electric switch 18 by an elongated electrically conductive strip 134 whose lower end is connected to the ferrule and anchored to the casing by said eyelet 132. Said strip lies in the wide lower portion of the channel 38. The strip is additionally anchored by a rivet 136 which is insulated from said strip by a non-conductive washer 138. Rivets 140, 142 aid in securing the strip to the casing and also assist in the operation of the switch 18. The latter is of the three step type, such as shown and described in my copending application Serial No. 377,983, this switch being particularly adapted for use with a flashlight casing of insulating material. The switch is adapted to make and break an electric circuit between the conductive strip 134 and another electrically conductive strip 144, which is disposed in the narrow upper portion of the channel 38.

The strip 144 is anchored to the casing and connected to the switch by a rivet 145. Said strip extends through the opening 40 in the semi-circular wall 34 beyond the top end of the channel 38 and through the slot 46. The strip 144 is also provided with a finger 146 which extends parallel to the longitudinal axis of the head portion 22 and toward the lens ring 70. The tip of said finger is adapted to engage the rear surface of the reflector 82 near the flange 80 and during such engagement the finger will be bowed between said reflector and the inner wall 46a of the slot 46 over the fillet 48, this bowing serving both to anchor the strip 146 and to insure good electric contact between said strip and the reflector as more fully explained in my copending application Serial No. 503,183; filed September 21, 1943.

The foregoing portion of the electrical system serves to form one leg of the electric circuit between the batteries B and the electric lamp, the current in this leg of the circuit passing in order from the zinc cup 66 through the spring 126, ferrule 130, strip 134, switch 18 (when closed), strip 144, reflector 82, ferrule 86 and flange 90 to the lamp.

Connection is made between the metallic tipped carbon electrode 68 and the center contact 98 of the lamp through a contact strip 148 of electrically conductive resilient material, such as phosphor bronze, having a base leg 150 held against a flat 152 at the bottom of the semi-circular wall 34. Said base leg is connected by a curved bend 153 to a forwardly inclined contact leg 154 which is adapted to press against the center contact 98 of the bulb. In relaxed position the contact leg 154 is disposed as shown in Fig. 6, the position thereof when the head assembly is attached being shown in Fig. 3.

The base leg 150 is secured to the wall 34 by an eyelet 155 of electrically conductive material whose lower end is spun over an electrically conductive washer 158 resting on a flat 159 beneath the wall 34, said washer and the base leg 150 serving to distribute the strain upon the wall 34 when setting the eyelet 156.

The metal clad carbon tip 68 is adapted to be pressed against the lower spun end of the eyelet 156 by the battery spring 126 to complete the circuit from said carbon electrode to the center contact of the lamp through the eyelet and the contact spring 148.

It will thus be seen that I have provided a device in which the several objects of the invention

are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

10 Having thus described my invention, I claim as new and desire to secure by Letters Patent:

1. An angle head flashlight comprising a one piece molded plastic casing, including a tubular battery receiving portion and a tubular head 15 whose axis of symmetry intersects the axis of symmetry of the battery receiving portion substantially at right angles, the ends of said battery receiving portion and head at said intersection being integrally connected, and a partition within 20 in said casing substantially closing off both said integrally connected ends, said partition being formed integrally with the casing and reinforcing the battery receiving portion and head against distortion and breakage.
2. An angle head flashlight comprising a one piece molded plastic casing, including a cylindrical tubular battery receiving portion and a cylindrical tubular head, the axes of symmetry of said head and battery receiving portion intersecting substantially at right angles, the walls of said head and battery receiving portion being integrally connected along a line of juncture around said intersection, and a portion of the wall of said head extending past said line of juncture within 30 said casing to substantially close off the end of the battery receiving portion connected to the head and reinforce said battery receiving portion and head against distortion and breakage.
3. An angle head flashlight comprising a one piece molded plastic casing, including a cylindrical tubular battery receiving portion and a cylindrical tubular head of substantially the same diameter, the axes of symmetry of said head and battery receiving portion intersecting substantially at right angles, the walls of said head and battery receiving portion being integrally connected along a line of juncture around said intersection, and a portion of the wall of said head extending past said line of juncture within 40 said casing to substantially close off the end of the battery receiving portion connected to the head and reinforce said battery receiving portion and head against distortion and breakage.
4. A flashlight as set forth in claim 3, wherein 55 an energizing electric system is provided for carrying current from a battery in the flashlight casing to a lamp also housed therein, said system including a conductive element which freely passes from the battery receiving portion to the head through an opening in the portion of the head extending into the casing.
5. A flashlight as set forth in claim 3, wherein 60 the battery receiving portion is elongated and has a channel formed internally therein and extending longitudinally thereof for receiving the bare conductive elements of an electrical system in said flashlight which are adapted to energize a lamp housed in the head from battery cells in said battery receiving portion, said channel leading to an opening in the wall of the head portion 65 extending within said casing whereby one of said elements may pass therethrough.
6. A flashlight as set forth in claim 1, wherein 70 a belt hanger is secured to the battery receiving portion near the end thereof integrally connected

to the head, said battery receiving portion being integrally thickened at the point of securement.

7. A flashlight as set forth in claim 1, wherein a belt hanger is secured to the battery receiving portion near the end thereof integrally connected to the head, said battery receiving portion being integrally thickened at the point of securement by a wide flat disposed internally of the casing and by a wide ridge disposed externally of the casing.

8. An angle head flashlight including a plastic casing having integrally connected tubular head and body portions angularly disposed relative to one another and an integral partition within the casing between said head and body portions to reinforce said casing against distortion and breakage, said partition having an integral wall projecting upwardly therefrom and defining one edge of an opening between said partition and casing, the edges of said wall being backed up by wings integrally connecting said wall to the casing, said wings defining two lateral edges of said opening.

9. An angle head flashlight including a plastic casing having integrally connected tubular head and body portions angularly disposed relative to one another and an integral partition within the casing between said head and body portions to reinforce said casing against distortion and breakage, said partition having an integral wall projecting upwardly therefrom and defining one edge of an opening through said partition, a resilient contact comprising part of an energizing electric circuit for carrying current from a battery in the flashlight casing to a lamp also housed therein, said contact element including a flat leaf spring, the base leg of said spring being secured to said partition, said leaf spring having a contact leg extending angularly to said base leg and pressing against said wall.

10. An angle head flashlight including a plastic casing having integrally connected tubular head and body portions angularly disposed relative to one another and an integral partition within the casing between said head and body portions to reinforce said casing against distortion and breakage, a pair of spaced parallel ridges formed internally and longitudinally of said body portion to define a channel for receiving bare conductive elements of an electrical system in said flashlight which are adapted to energize a lamp housed in the head portion from battery cells contained in said body portion, said channel extending through an opening in the partition.

11. In a device of the class described, a molded insulation casing having a substantially elongated shell and an angularly formed head integral therewith at one end, a bulb and reflector assembly carried by said head, a cap including a lens for holding said assembly positioned within said head, conductors in said shell arranged for electrical connection with a source of current supply disposed in said shell, one of said conductors comprising a bar extending along the wall of said shell and having an angularly turned portion at its forward end to extend into said angular head, said angularly turned portion being resiliently formed and being arranged to press resiliently against said reflector to establish an electrical contact therewith, and a shelf integrally formed with the wall of said head for holding said bar in a manner to keep said resilient portion in position against the reflector.

12. In a device of the class described, a molded

insulation casing having a substantially elongated shell and an angularly formed head integral therewith at one end, said shell including spaced longitudinally extending ribs formed integrally with said shell, a bulb and reflector assembly carried by said head, a cap including a lens for holding said assembly positioned within said head, conductors in said shell arranged for electrical connection with a source of current supply disposed in said shell, said conductors lying between said spaced ribs and out of contact with said source of current supply along the length of the ribs, one of said conductors comprising a bar extending toward said head and having an angularly turned portion at its forward end thereby to extend into said angular head, said angularly turned portion being resiliently formed and being arranged to press resiliently against said reflector to establish an electrical contact therewith.

13. In a device of the class described, a molded insulation casing having a substantially elongated shell and an angularly formed head integral therewith at one end, said shell including spaced longitudinally extending ribs formed integrally with said shell, a bulb and reflector assembly carried by said head, a cap including a lens for holding said assembly positioned within said head, an interior annular conducting ring fastened to the end of said shell spaced from said angular head, a pair of conductors in said shell arranged for electrical connection with a source of current supply disposed in said shell, said conductors lying between said spaced ribs and out of contact with said source of current supply along the length of the ribs, one of said conductors comprising a bar extending toward said head and having an angularly turned portion at its forward end to extend into said angular head, said angularly turned portion being resiliently formed and being arranged to press resiliently against said reflector to establish an electrical contact therewith, the other of said conductors extending toward and being connected to said annular ring.

14. In a device of the class described, a molded insulation casing having a substantially elongated shell and an angularly formed head integral therewith at one end, a bulb and reflector assembly carried by said head, a cap including a lens for holding said assembly positioned within said head, conductors in said shell arranged for electrical connection with a source of current supply disposed in said shell, an integral molded partition bridging said shell substantially adjacent the junction of said shell and said head, there being an opening between said partition and the interior wall of the shell to provide a passage for one of said conductors to extend from said shell into said angular head, a shelf associated with the wall of said head adjacent said opening for holding said one of said conductors extending through said passageway, a conductor element carried by said partition, portions of said conductor element exposed on opposite sides of said partition, one of said portions comprising a terminal connection for one of the terminals of said source of supply, and a spring finger held by said other portion to form a contact member for one of the terminals of the bulb of said assembly carried by said head.

15. In a device of the class described, a molded insulation casing having a substantially elongated shell and an angularly formed head integral therewith at one end, spaced longitudinally

75

extending ribs integral with said shell and forming a channel, a bulb and reflector assembly carried by said head, a cap including a lens for holding said assembly positioned within said head, conductors in said shell lying within said channel and arranged for electrical connection with opposite terminals of a source of current supply disposed in said shell, an integrally molded transverse partition disposed at the juncture of said shell and said head and extending thereacross, said partition forming an abutment against which said source of current supply is held, there being an opening between said partition and the interior wall of said shell, said opening registering with said channel for one of said conductors to extend from said shell along said channel and into said angular member, a finger carried by said partition and against which the bulb of said assembly carried by said head yieldably presses, and a fastening member for said finger mounted upon said partition and having means extending through said partition substantially centrally thereof, said means being exposed on the side of said partition opposite to said finger to form a terminal connection for one of the terminals for said source of current supply.

16. In a device of the class described, a molded insulation casing having a substantially elongated shell and an angularly formed head integral therewith at one end, spaced longitudinally extending ribs integral with said shell and forming a channel, a bulb and reflector assembly carried by said head, a cap including a lens for holding said assembly positioned within said head, conductors in said shell lying within said channel and arranged for electrical connection with a source of current supply disposed in said shell, one of said conductors comprising a bar extending along the wall of said shell and having an angularly turned portion at its forward end thereby to extend into said angular head, said angularly turned portion being resiliently formed and being arranged to press resiliently against said reflector to establish an electrical contact therewith, and a shelf integrally formed with the wall of said head, said shelf being in line with said channel for receiving said bar and holding said bar in a manner to keep said resilient portion in position against the reflector.

17. In a device of the class described, a molded insulation casing having a substantially elongated shell and an angularly formed head integral therewith at one end, a bulb and reflector assembly carried by said head, a cap including a lens for holding said assembly positioned within said head, conductors in said shell arranged for electrical connection with opposite terminals of a source of current supply disposed in said shell, an integrally molded transverse partition disposed at the juncture of said shell and said head and extending thereacross, said partition forming an abutment against which said source of current supply is held, there being an opening between said partition and the interior wall of said shell, one of said conductors extending from said shell through said opening and into said head, a finger carried by said partition and against which the bulb of said assembly carried by said head yieldably presses, and a fastening member for said finger mounted upon said partition and having means extending through said partition substantially centrally thereof, said means being exposed

on the side of said partition opposite to said finger to form a terminal connection for one of the terminals for said source of current supply.

18. An angle head flashlight including a plastic casing having integrally connected tubular head and body portions angularly disposed relatively to one another and an integral transverse partition within the casing disposed at the juncture of said head and body portions to reinforce said casing against distortion and breakage, there being an opening between said partition and the interior wall of said body portion, a pair of spaced parallel ridges formed internally and longitudinally of said body portion to define a channel for receiving bare conductive elements of an electrical system in said flashlight which are adapted to energize a lamp housed in the head portion from battery cells contained in the body portion, said channel extending through said opening.
19. An angle head flashlight comprising a one-piece molded plastic casing, including a tubular battery receiving portion and a tubular head whose axis of symmetry intersects the axis of symmetry of the battery receiving portion substantially at right angles, the ends of said battery receiving portion and head at said intersection being integrally connected, a bulb and reflector assembly carried by said head, a cap including a lens for holding said assembly positioned within said head, conductors in said casing arranged for electrical connection with a source of current supply in said battery receiving portion, and a transverse partition within said casing disposed at the juncture of said battery receiving portion and head, said partition being integral with the casing and reinforcing the battery receiving portion and head against distortion and breakage, there being an opening between said partition and the interior wall of said battery receiving portion, through which one of the conductors extends from said battery receiving portion to said head, and there being an opening in said partition at substantially the axis of symmetry of the battery receiving portion, through which second opening another conductor extends from said battery receiving portion into said head.
